WILHELM KUMMERER, OF BERLIN, GERMANY, ASSIGNOR TO TELEFUNKEN GESELLSCHAFT FÜR DRAHTLOSE TELEGRAPHIE M. B. H. HALLESCHES, OF BERLIN, GERMANY, A CORPORATION OF GERMANY

TRANSMITTER-TUBE ARRANGEMENT

Application filed February 20, 1928; Serial No. 255,797, and in Germany March 29, 1927.

In tube transmitter arrangement working with comparatively large powers and in which the working potentials of the tube are derived from a high-potential network, it is necessary, as is well known, to have recourse to what is known as a load-balancing arrangement, by which during the intermissions in keying (spacing) when the transmitter oscillations cease or are diminished, a separate circuit serves to load the potential source. By the aid of such a load compensating (ballasting) circuit, over-voltages, of the kind as would arise if the load of the supply line or of the potential source were suddenly interrupted during the keying intermissions, are avoided.

The circuit provided for the load compensating usually contains a distinct tube, suitably of the three electrode type whose conductance is varied in dependence upon the keying, so that while sending or keying signals, in other words, during the periods when oscillations are radiated from the transmitter apparatus, the said tube is non-conducting so that no loading of the network is present, whereas during the spacing times the tube is rendered conducting, thus representing the load of the network. According to former practice, this load-compensating tube was mechanically controlled in dependence upon the operation of the transmitter key; that is, the grid was fed with corresponding direct current biasing potentials. Hence, in circuit arrangements of this kind, a distinct key is furnished for the load equalizing (ballasting) tube which operates in dependence upon the key of the transmitter.

The subject-matter of the present invention is embodied in the drawing in which the single figure shows a special form of construction of the load-balancing or ballasting circuit which depends upon the fact that the load-balancing tube is automatically controlled by the radio frequency energy of the transmitter so that the conductance of the load-balancing tube is varied in dependence upon the intensity of the oscillations of the transmitter. When the transmitted waves are of high intensity, that is to say, while signal transmission is proceeding, the conduc-

tance must be diminished, while when the intensity is small, the conductance must be increased. One suitable arrangement consists in that a distinct circuit is provided which comprises a rectifier device, say, a two-electrode tube to which the transmission waves are supplied so that rectified currents are flowing in this circuit. From a resistance contained in this circuit a potential is applied to the grid and the cathode of the load-balancing tube in a sense such that the radio frequency oscillations of the transmitter produce a negative rectifier direct current biasing potential which is applied to the load-compensating tube.

In the single figure of the drawing, 1 denotes the transmitter tube, or one of the tubes of the tube-transmitter apparatus, for example, a tube in the power amplifier. Connected with the same power supply network 2, 3, is a load-compensating tube 4, connection being established by way of a choke-coil 5 or a corresponding resistance. With the resonance circuit 6 of the transmitter apparatus there is coupled a circuit which includes the rectifier 7 and a condenser 8. From this condenser, a branch is brought to the grid and filament of the load-compensating tube (ballasting tube), while shunted to the grid there is a resistance 9.

The function of this circuit arrangement is as follows:

The higher the intensity of the oscillations of the transmitter 1, the higher naturally will be the negative potential developing across the condenser 8, and the higher also the negative biasing potential of the grid of tube 4. By the convenient dimensioning of the circuits and the constituent circuit elements it is possible to create conditions so that the load of the network during signal transmission and during spacing periods remains nearly unvaried. In this arrangement as will be noted, no distinct key in the grid equalizing circuit is necessary, and the balancing of the load is accomplished automatically.

Having thus described my invention what I desire to protect by Letters Patent is as follows:

1. In a device for maintaining a constant

100

load on a power supply system for transmitter tube circuits, an oscillatory tube system having an oscillation circuit therein, a load balancing tube and means comprising a rectifying circuit controlled by the intensity of oscillations in the transmitter circuit for influencing said load balancing tube.

2. A device for maintaining the load on a power supply system for transmitter tube circuits constant, comprising an oscillatory tube system having an oscillation circuit therein, a three electrode load balancing tube and a rectifying circuit, means for controlling the energy in said rectifying circuit in accordance with the intensity of oscillations in the oscillatory circuit for affecting the load taken up by said balancing tube.

3. In a device for maintaining a constant load on a power supply system for transmitter tube circuits, an oscillatory tube system having an oscillation circuit therein, a load balancing tube connected to the power supply line and means comprising an energy transferring circuit between said oscillatory circuit and said load balancing tube for affecting the conductivity of said load balancing tube in accordance with the oscillations in said transmitter circuit.

4. In a device for maintaining a constant load on a power supply system for transmitter tube arrangements, an oscillatory tube system having an oscillation circuit therein, a load balancing tube of the three electrode type having its plate filament circuit connected across the power supply line, the grid filament circuit of said tube having therein a condenser and a resistance in parallel, and a rectifying device coupled with said oscillatory circuit and arranged in series with said condenser for charging said condenser in accordance with conditions in said oscillatory circuit.

5. In a device for maintaining a constant load in a power supply system for vacuum tube circuits, a transmitting arrangement having an output and an input circuit, said output circuit comprising an oscillation circuit and said power supply system in series, a variable loading device shunted across said power supply system, said variable loading device having an input and an output circuit and having similar electrical characteristics as said transmitting arrangement, means comprising a rectifying device for coupling the output of said transmitting arrangement to the input of said loading device said last named means being adapted to reverse the function of said loading device relative to said transmitting arrangement.

6. In a transmitter, means for generating oscillations including a thermionic tube, a source of potential therefor, a load balancing tube having its anode cathode impedance connected across said source, an oscillatory circuit in said oscillation generating means, and

means comprising a rectifier and condenser in series coupled with said oscillation circuit for effecting the impedance of said balancing tube.

7. In a device of the kind described a power supply system, a signal transmitting arrangement connected to said power supply system, said arrangement having load characteristics varying in accordance with the transmitted signal energy, an auxiliary loading means connected to said power supply system, means for coupling said transmitting arrangement to said auxiliary loading means, said last named means being adapted to increase the effect of said loading means on said power supply system when the effect of said transmitter on said power supply system decreases and vice versa.

8. In apparatus to be used with an oscillation generator of the thermionic type wherein the anode cathode impedance of said thermionic type is connected across a source of direct current potential in series with an oscillation circuit, the combination of an auxiliary triode having its anode cathode impedance connected across said source, of a rectifier connected in series with means coupled to said oscillation circuit and with an impedance connected between the control electrode and the cathode of said auxiliary triode.

9. In combination, an electron discharge device having an anode-cathode circuit, a source of electromotive force connected in said circuit, a second electron discharge device connected across said source of electromotive force, means for controlling said first discharge device in accordance with desired signals and additional means responsive to operation of said first device to control the impedance of said second electron discharge device thereby to compensate for impedance variations in the first electron discharge device.

10. In an oscillation system an electron discharge device having output electrodes connected in an output circuit, means for supplying energy to said device, a variable loading device shunted across said energy supply means, and means in said output circuit for controlling said variable loading device in accordance with the load placed upon said supply means by said electron discharge device in opposite senses whereby the total load of said energy supply means remains constant.

11. The combination in a signal system of an electron discharge device having an anode, a cathode, and an output circuit associated with said anode, means for producing oscillations on the anode of said discharge device, an oscillatory circuit in said output circuit, a source of electromotive force connected between said anode and said cathode, the magnitude of the oscillations on said anode

and in said oscillation circuit being dependent in part on the electromotive force supplied to said anode, a second electron discharge device having an anode and cathode connected in shunt with the anode and cathode of said first named device and arranged normally to draw appreciable current from said source, and means responsive to oscillations on the anode of the first named

5 discharge device for alternately transferring a portion of the load on said source from one of said devices to the other, thereby to prevent variations in potential in said source due to changes in magnitude of the load

15 thereon.

12. In a signal transmitter, an electron discharge device having an anode-cathode circuit, a source of electromotive force connected in said circuit, a second electron discharge device connected across said source of electromotive force, means whereby said first discharge device is excited with high frequency oscillations in accordance with desired signals, and means for controlling said

20 second electron discharge device in response to said oscillations thereby to maintain a substantially constant load on said source notwithstanding impedance variations in said first discharge device.

25

30 13. The combination in a signal system of an electron discharge device having an operating circuit, a signal device included in said system, the impedance of said operating circuit being variable in response to operation of

35 said signal device, a source of energy for said operating circuit, and means controlled by the signal device for producing an additional load on said source when the impedance of said operating circuit is increased thereby to

40 compensate for variations in load on said source produced by variations in impedance of the operating circuit.
